[57] ABSTRACT

A device for exerting an adjustable pressure against one side of continuously moving web of a rigid strip material having the other side thereof contacted by a surface treatment apparatus, including one or more blocks connected to a source of pressurized gaseous medium and having a plane surface in proximately spaced relationship with the first mentioned surface of the web, the surface having gas passageways therein so as to follow the formation of a gas cushion between the web surface and the block which prevents direct contact therebetween while concurrently imparting pressure to the surface of the web in the direction of the surface treatment apparatus.

APPARATUS FOR APPLYING PRESSURE TO AN ADVANCING WEB OF RIGID MATERIAL

This invention relates to devices for exerting an adjustable pressure on a given portion of one side of rigid strip material which is being carried past continuously. The other side of the strip rests against any other suitable apparatus, which may optionally perform a treatment on the other side.

Devices of this nature are employed in glass production lines employing the so-called "float glass" process. In these it may be profitable to impart a finish to the lower side of the strip or web.

At present these devices apply the lower side of the glass web against the "felts" of a polishing apparatus. Also a plane surface made up from a series of parallel rollers arranged on a frame permits freeing of the glass web. In use the frame which can be moved vertically, depresses the rollers onto the upper side of the web and applies the lower side against the felts of the polishing plates. The pressure exerted on the felts depends on the weight of the frame and of the rollers. Counterweights are generally incorporated which enable the exerted pressure to be varied. The rollers are journaled on bearings and have their axes perpendicular to the direction of travel of the web.

These devices suffer from the following shortcomings:

- i. the pressure applied by the rollers to the glass web operates through the contacting surfaces of the rollers, and this area is necessarily small. The pressure is designed to be transmitted as uniformly as possible, so that the polishing work is spread over the glass surface;
- ii. the rollers rest on glass and they are caused to rotate by the forward moment of the web;
- iii. sudden local variations in thickness in the web cause the complete frame to rise, resulting in a substantial local overpressure;
- iv. if a narrow web for a given frame is used, the rollers project beyond the web which causes premature deterioration of their rubber facing.

The present invention provides a device comprising one or more blocks whose weight is controllable and whereof the face facing towards the web is furnished with elements allowing the passage of a gas under pressure, in such manner as to form a gaseous cushion preventing direct contact between the web and the block or set of blocks.

The weight of blocks can be adjusted by the addition or removal of units of a given weight.

A plurality of small orifices or discs of porous material can be attached to the plane lower surface of each block to allow gas to emanate from each block. Conveniently a flexible hose is used to feed gas under pressure to each block.

The block or set of blocks is carried on a frame capable of being raised in order to free the web. Optionally each block of the set of blocks may be raised separately. In this way the spread of the gaseous cushion can easily be matched to the width of the web.

The presence of a gaseous cushion between the blocks and the web can reduce frictional forces opposing the displacement of the web.

The block surfaces facing towards the web can be plane and parallel to that of the web so that the pressure corresponding to the weight of the blocks exerted onto the web is distributed uniformly.

Because the blocks are independent, superfluous blocks can easily be withdrawn when the web width is changed. Any local variation in the thickness of the web should not produce a substantial local overpressure, for the blocks being used are arranged to match the thickness of the web.

The pressure of the gas is adjusted depending on the weight of the blocks and on the cushion thickness required. To polish the lower side of the web, the pressure through the gaseous cushion exerted by the blocks against the upper side of the web should be approximately 20 kgs/dm².

The present invention is described by way of a non-limiting example with reference to the accompanying drawings.

FIG. 1 is a section of the device taken along the line I—I of FIG. 2 in a plane perpendicular to the direction of travel of the web;

FIG. 2 is a section taken along the line II—II of FIG. 1;

FIGS. 3 and 4 are sections on an enlarged scale of two kinds of block.

The plant comprises a polishing appliance 1 in which the felts 2 are in contact with the side 3 of the glass web 4.

The surface 3 is applied against the felts under pressure through a device which, according to the invention, comprises adjacent blocks 5 held within a frame 6. This frame 6 can be raised by means of jacks 7, designed to withdraw, if need be, the set of blocks 5 from the side 8 of the web.

On top of each block 5 is fastened by means of screws 9 a plate 10, the dimensions of which are a little smaller than the lower part 5' of the block, but greater than those of the upper part 5''. Hence recesses 11 are formed within the blocks, in which the elements of the frame 6 can fit. Each block 5 can move up and down freely in a vertical direction as defined by the limits of the recesses 11. Each block contains a distribution system from gas under pressure entering through a pipe 12 screwed onto the block and connected to the duct 13 by means of a flexible hose 14. The pipe 12 fits onto a passage 15 passing through the block. The passage 15 opens into a cavity 16 defined by the block 5' and a "sole" 17 which is secured to the former by means of the screws 18. Either nozzles 19 (FIG. 3) with a lower orifice of small diameter, or porous discs 20 (FIG. 4) are arranged in this sole plate. The gas under pressure maintains a gas cushion between the plane lower surface of the sole plate 17 and the upper side 8 of the web 4. The thickness of the gas cushion should be as thin as possible without allowing direct contact between the set of blocks 5 and the side 8 of the web.

Each block can be withdrawn separately from the web 4 by causing an abutment 21 secured to the pipe 12 to be lifted by the cross-member 22 of the frame. Thus the number of blocks in use can be adjusted for the width of the web.

The weight of each block 5 and the pressure on the web through the gas cushion is adjusted by adding or removing from block 5 weights 23 equal in size to the plate 9.

The gas, for example air, which enters through the duct 13 will first have passed through a pressure-control device (not illustrated). The pressure level is deter-

mined by the required air cushion thickness, as well as the weight of the blocks. The gas air feed to unused blocks can be shut off by cocks 24.

The invention is evidently not limited to the embodiments which have been described and illustrated in the example, and its scope would not be exceeded by making modifications in these.

I claim

1. Device for exerting an adjustable pressure against one surface of a web continuously conveyed therewith and the other surface of which is being contacted by a surface treatment apparatus, said device comprising; at least one block having a plane surface facing toward said first-mentioned surface of the web; means for adjusting the weight of said block; means for supplying a flow of a pressurized gaseous medium through said block toward said plane surface; means positioned in said block allowing passage of said gaseous medium through said plane surface so as to form a gas cushion intermediate the plane surface and said web to thereby prevent contact between said block and said web while concurrently imparting pressure on said web in the direction of the surface treatment apparatus.

2. Device as claimed in claim 1, said means allowing passage of said gaseous medium through said plane sur-

face comprising at least one small diameter orifice communicating said gaseous medium supplying means with said plane surface.

3. Device as claimed in claim 1, said means allowing passage of said gaseous medium through said plane surface comprising gas-pervious porous discs positioned in said block.

4. Device as claimed in claim 1, comprising removable weights adapted to be mounted on said block for adjusting the weight thereof.

5. Device claimed in claim 1, comprising frame means supporting said block; and means for raising said frame means for lifting said block away from said web.

6. Device as claimed in claim 1, said gaseous medium supplying means comprising a flexible hose connected to said block.

7. Device as claimed in claim 1, comprising a plurality of said blocks extending laterally across the width of said web for imparting pressure thereagainst.

20 8. Device as claimed in claim 7, comprising frame means supporting each of said blocks, said blocks being individually removable from said frame means for correlating the quantity of blocks with the width of said web.
